CLAIM

We claim the ornamental design for a LED lamp, as shown and described.

DESCRIPTION

FIG. 1 is a front perspective view of a LED lamp showing our new design;

FIG. 2 is a front view of the LED lamp of FIG. 1;

FIG. 3 is a rear view of the LED lamp of FIG. 1;

FIG. 4 is a left side view of the LED lamp of FIG. 1;

FIG. 5 is a right side view of the LED lamp of FIG. 1;

FIG. 6 is a top view of the LED lamp of FIG. 1;

FIG. 7 is a bottom view of the LED lamp of FIG. 1; and,

FIG. 8 is a front perspective view of the LED lamp of FIG. 1 shown in use with a holder for a LED lamp; and with an enlarged partial view shown in the dash-dot-dash circle.

The broken lines in the drawings illustrate unclaimed environmental structures and a holder for a LED lamp, which form no part of the claimed design.
